THERMIONIC TUBE SOCKET

Hugh H. Eby, Philadelphia, Pa., assignor to Hugh H. Eby, Inc., Philadelphia, Pa., a corporation of Pennsylvania

Application July 30, 1937, Serial No. 156,481

4 Claims. (Cl. 173—339)

This invention relates to thermionic tube sockets, and more particularly to radio tube socket receptacles.

In application Ser. No. 148,546, filed June 16, 5 1937, I disclosed improvements in radio tube sockets, a feature of which was the mounting of a socket base, either of unitary or multi-piece construction, in a metallic mounting support. The instant invention comprises improvements 10 on the disclosures of that application, as well as improvements in the art generally.

It is among the objects of this invention; to reduce the costs of radio tube sockets; to provide a radio tube socket of extreme simplicity; to provide a radio tube socket of conventional strength but of small mass and weight of materials; to improve the sockets disclosed in the earlier filed Eby applications, Ser. Nos. 25,369 filed June 7, 15 1935, now Patent No. 2,127,556 of August 23, 1938; and 25,055 filed June 5, 1935, now Patent No. 2,196,697 of April 9, 1940; to improve the details of radio tube sockets; to provide an assembled radio tube socket arranged for snap-in sub-assembly mounting; to provide a radio tube socket arranged for snap-in assembly and for snap-in sub-assembly mounting; and many other objects and advantages as will become more apparent as the description proceeds.

In the accompanying drawing:

Fig. 1 represents a plan of a metal stamping or pan according to one form of the invention,

Fig. 2 represents an elevation, partially broken away, on an enlarged scale, of the stamping of Fig. 1,

Fig. 3 represents a plan of the assembled metal stamping of Fig. 1 and the socket receptacle mounted thereon,

Fig. 4 represents a fragmentary vertical section through a portion of the assembled socket and mounting support of Fig. 3,

Fig. 5 represents a fragmentary section through a further modification of the mounting support, showing a different form of anchoring element,

Fig. 6 represents a fragmentary perspective of 45 a portion of the mounting device of Fig. 7.

In carrying out the invention in certain of its broader aspects, a metal plate is provided having an integral securing means extending from it, and a socket receptacle is held to the plate by a 50 portion of the securing means.

In the disclosure of the application 148,546 it was shown that a metal stamping or cage having a recess to receive a socket base could be associated with the base, with means to anchor the 55 parts together. A cage or metal stamping simi-

lar in its broader aspects to that of said application, is shown in some of the figures in this application.

Referring to Fig. 1, the pan or metal stamping comprises the upper plane portion 10 merging into the securing ears 11 having the mounting apertures 12, to receive eyelets or the like for securing the socket assembly on a panel of a chassis of the radio set, or the like. The well to receive the base is comprised of the substantially cylindrical wall 13, integral with the upper portion 10, terminating in the short inwardly extending flange 14. The stamping thus described may be provided with the vertical rib 15 stamped from the metal of the cylindrical wall, to serve as a device for preventing rotation of the base in the stamping, as well as for indexing the base in the stamping, as will be explained. In the form of stamping shown in Fig. 1, it is a feature of importance that a plurality of downwardly extending tongues 16 are formed in the cylindrical wall of the stamping, terminating in a locking edge 17 a predetermined distance from the plane of the flange 14, controlled by the thickness of the lower plate or lamination to be described. In this connection it may be observed that the flange 14 may be slotted radially, as shown, to form a plurality of bendable fingers 18, some at least of which can be bent up from the plane of the flange to receive resiliently the lower plate to be described, to yield during seating of such plate to a point only at which the tongue edge 17 engages such plate firmly and positively for anchoring to accord with variations in thickness of laminations, or variations in gauge of metal used in forming contacts.

The provision of the fingers in the flange by the radial slots shown, which was shown in the application Ser. No. 148,546, leads to another feature of the invention which should be noted. In the said last mentioned application in Fig. 73 there was disclosed a fragment of a mounting pan in which the flange of the pan carried a perpendicular flange or finger, substantially as shown in Fig. 4B herein. Reference to Fig. 2 40 discloses a figure that is identical with the said Fig. 73 noted, except that the finger extends perpendicularly of the flange in the opposite direction to proximity to certain of the socket contacts. In practice it may be preferred to form several 45 fingers, illustratively four, for instance, as indicated in dotted lines at 7, which are bent to perpendicularity to the flange 14 as shown at 8. While desired pairs might be used for any desired purpose such as might arise in the radio 50 55

art, the fingers 8 are preferably arranged with suitable scoring or lines of weakness to be easily broken off when not desired for use, to leave that one or more that is desired, if any, in the given 5 installation.

The multi-part base of this invention may be formed of two sheets of insulating material, such as the molding material known as "low loss" material, or any of the phenolic resins, or the like, or may comprise those insulating sheets known as laminated. Illustratively a lower sheet or plate 21 preferably shaped so as to be received within the cylindrical wall 14 has a large central round aperture 22, and a plurality of contact 10 15 receiving apertures 23 disposed in a concentric circle in the plate. Broadly the shape of the contact apertures and the nature of the contacts 24 may be varied as desired.

A top or cover plate 34 is superimposed upon 20 the first plate (21), and has prong contact apertures 35 arranged for substantial registration with the contact apertures 23, or with the prong passage 62 in the contact mounted therein, and also has a central aperture 36. The top and 25 bottom plates are each provided with a lateral recess, respectively 37 and 38, communicating with the respective central apertures 26 and 22, and forming an indexing guiding groove portion of the registering guide apertures, to receive the 30 axial guide protuberance on certain types of radio tubes possessed of a lateral key, tongue, or rib, as is common in the art. It is preferred that the two plates be held rigidly together by an eyelet 40 having the bottom flange 41 engaging under bottom plate 21, the upper flange 42, swaged over the upper surface of the top plate 34, and with a portion of the eyelet engaging laterally in the registering recesses 37 and 38, or the groove formed thereby, as at 43. This serves the excellent 35 cause of simultaneously anchoring the plates together, preventing their relative rotation, securing a guide rib recess, protecting the material adjacent to the recess with a metal overhang, secures symmetrical support during axial 40 pressure from tube insertion, enabling the use of thinner sheets of material, and obviates the use of additional securing means between the plates.

The composite base thus formed is associated 50 with the pan or mounting support of Fig. 1, by simply pressing the complete base axially downwardly into the well of the pan, until the edge of the lower plate has pushed the resilient tongues 16 outwardly toward the surface of the 55 wall 14 until the lower edge 17 of each clears the upper edge of the lower plate, pursuant to which the tongues spring inwardly to engage upon the upper surface of the lower plate to hold the assembly in anchored relation. In this connection 60 it is preferred that in predetermined angular relation to the guide recesses in the central apertures of the respective plates, there will be indexing indentations 44, arranged to engage upon the indexing rib 15 of the stamping. Such indentations may be of any number from one on, but preferably there will be four disposed in such 65 relation as to enable 90° indexing between the assembled composite base and the metal stamping or mounting support. Obviously after the 70 assembly of the pan and base of Fig. 3 has been secured, the parts are anchored, but this relation can be interrupted by pushing any thin object downwardly to retract the resilient tongues to permit reinindexing or disassembly.

75 The indexing peripheral slots of the assembled

socket of Fig. 3 may be disposed in the lower plate only in order to leave the upper plate free from visible unnecessary apertures. In this case, of course, the rib 15 would be terminated close to flange 14.

It will be clear that the assembled mounting support and multi-part socket or base is a cheap and simple construction, and that by means of the mounting ears it can easily be secured upon a panel of a chassis of a radio set or the like. 10

In Figs. 5 and 6 a modified form of pan is disclosed in which the wall 13 has an arcuately prolonged indentation or boss 46, disposed high in said wall so as to be arranged to frictionally engage the upper plate 34 of the composite base of 15 the earlier figures, or of a form of base which is not previously secured together. It will be clear that with the boss shown, provided in such numbers as may be found expedient, perhaps two or four thereof, that the lower plate 21 with the 20 several female contacts disposed in the contact apertures thereof may be pushed into the well of the mounting support, then the upper plate 34 may be pushed into the well of the mounting support and the act of associating the upper 25 plate with the lower also anchors them together. In this case it is preferred that the indexing rib be of such vertical extent as to engage both plates so as to prevent relative rotation of the plates. In Figs. 5 and 6 the boss 46 is on a tongue 30 slotted in wall 13 to impart resilience.

In the forms of invention just described it has been suggested that the assembly of mounting support and socket element or base be by the formation of a veritable housing in which the 35 base was mounted. This is a desirable form.

I claim:

1. In radio tube sockets, a supporting plate including an aperture, a socket supporting element mounted integrally on the plate and extending 40 at least partially into the aperture in position to positively stop a socket passing into the aperture in the plate, a substantially perpendicular wall integrally extending from the plate at the side of the aperture toward the supporting element, 45 an integral resilient tongue struck out of the wall and having a laterally protuberant portion normally extending into the aperture, a multi-part socket receptacle associated with the plate and disposed on the supporting element, said 50 socket arranged to engage and deflect the said protuberant portion to enable the socket to engage the supporting element, and said tongue arranged to return substantially to its normal 55 resilient positioning to engage said socket to hold it engaged with the supporting element.

2. In radio tube sockets, a supporting device having a wall and a flange, a resilient tongue formed in the wall extending away from the flange and providing a curved shoulder spaced 60 from the flange, and a socket receptacle formed of two layers associated with said device and having a portion of both layers in the space between the shoulder and the flange to hold the receptacle and device together. 65

3. A mounting support for a radio tube socket comprising a plate having a depending wall and an integral supporting flange, and a resilient finger having a curved shoulder toward its free end formed in the wall and extending away from the flange so that the curved shoulder is spaced from the flange a distance proper to receive the radio tube socket element to cause a socket element resting upon the flange to be held against movement away from the flange by said curved shoul- 70 75 80 85 90 95

der overhanging an upwardly presenting surface of said socket.

4. A mounting support for radio tube sockets comprising a plate having a depending wall and a supporting flange, the supporting flange including an independent finger resiliently inclined out of the plane of the flange in such position as to yieldingly receive a radio tube socket, a resilient finger having a surface presented toward the flange in spaced relation thereto to engage an upwardly presenting surface of an inserted radio

tube socket, and the first mentioned finger being capable of distortion to lie substantially in the plane of the flange in accounting for radio tube sockets of appreciable thickness but arranged to urge thinner radio tube sockets away from the level of the flange to engagement with the downwardly presenting surface of the second mentioned finger so that radio tube sockets of varying thickness are anchored securely to the mounting support.

HUGH H. EBY,
